UNITED STATES PATENT OFFICE.

GEORGE E. WHITNEY, OF YONKERS, NEW YORK, ASSIGNOR TO THE INTERNATIONAL PAVEMENT COMPANY, OF HARTFORD, CONNECTICUT, A CORPORATION OF CONNECTICUT.

ASPHALT-BLOCK COOLER.

1,033,751.

Specification of Letters Patent. Patented July 23, 1912.

Application filed November 5, 1909. Serial No. 526,364.

To all whom it may concern:

Be it known that I, GEORGE E. WHITNEY, a citizen of the United States, residing at Yonkers, in the county of Westchester, State 5 of New York, have invented an Improvement in Asphalt-Block Coolers, of which the following description, in connection with the accompanying drawings, is a specification, like letters on the drawings representing 10 like parts.

This invention relates to asphalt block coolers.

In order that the principle of the invention may be readily understood, I have disclosed a selected embodiment thereof in the 15 accompanying drawings, wherein—

Figure 1 is a plan view of that end of an asphalt block cooler embodying my invention that receives the heated blocks from 20 the press; Fig. 2 is a vertical sectional view of the construction shown in Fig. 1, and illustrating also a portion of the press; Fig. 3 is a plan view of a part of the intermediate portion of the asphalt block cooler; Fig. 25 4 is a vertical sectional view of that portion of the cooler shown in Fig. 3; Fig. 5 is a plan view of the discharge end of the cooler; Fig. 6 is a view mainly in side elevation of the construction shown in Fig. 5; and Fig. 30 7 is a view, partially in transverse vertical section and partially in end elevation, of an asphalt block cooler embodying my invention.

Referring more particularly to the drawings, the press from which the asphalt blocks—composed of a stony mixture united by a bitumen bearing binder—are received by the cooler is indicated at 1 in Fig. 2, it being of any approved type. In practice, 35 blocks are discharged from the press in a highly heated condition, the temperature thereof approximating 300° F. In order to prevent deformation of the blocks it is important that they be effectively cooled immediately upon their discharge from the press and that they be not handled prior to the cooling thereof. Any handling to which the blocks may be subjected prior to their cooling increases their tendency to lose their 45 shape and condition.

It has heretofore been the common prac-

tice to cool or rather, to attempt the cooling of blocks discharged from an asphalt press by conveying them through a cooling liquid contained within a trough and flowing in 55 the direction of travel of the block conveying means, the blocks being received in the cooling trough at the cooling liquid inlet end thereof in a highly heated condition, and being at once acted upon by the coldest 60 portion of the liquid. This has resulted in the immediate lowering of the temperature of the surface of the blocks and the immediate raising of the temperature of the cooling liquid, so that before the blocks have traversed the length of the trough the temperature of the blocks or of their surfaces and that of the liquid are approximately the 65 same. Therefore in the remainder of the travel of the blocks through the trough the 70 cooling liquid has very little if any, further cooling effect thereon.

In accordance with the preferred embodiment of my present invention, I introduce the cooling liquid into the trough, through 75 which the blocks are conveyed, preferably at or adjacent the bottom thereof, and preferably at a series of longitudinally separated points, and as the cooling liquid, heated by contact with the blocks, rises to the 80 surface, I remove the surface film or layer of the now heated liquid and discharge the same from the trough, preferably laterally thereof, and in the present embodiment of the invention along the entire longitudinal 85 extent of the trough. In this manner, the blocks are subjected throughout their travel in the trough to the action of a cooling liquid of minimum temperature, and as the heated portion of the liquid is constantly 90 discharged, the temperature of the liquid is not unduly raised at any point by contact with the heated blocks. The result is that the blocks are effectively cooled when they reach their point of discharge from the 95 trough. Preferably I provide means to control the entrance of the cooling liquid into the trough at each of the admission points, so that if I find at any point along the length of the trough the surface temperature 100 of the cooling liquid is sufficiently low to cool the blocks, I may reduce or cut off the

admission of the liquid at or adjacent this point and introduce it only at such other points as may be indicated as necessary by the more highly heated condition of the surface liquid.

The trough or receptacle wherein the blocks are received to be cooled may be of any suitable dimensions, construction and material. Herein I have represented the same as metallic and as composed of any suitable number of sections 2 suitably secured together as through the medium of angle irons 3, a part only of the said sections being herein indicated. The trough or receptacle is represented as supported upon a series of uprights or chairs 4, each of which, as most clearly shown in Fig. 7, has an upper, substantially rectangular head 5 provided with a seat 6 for the cooling trough and a supporting post or pillar 7 provided, if desired, with a base 8.

While any suitable means may be employed to convey the blocks 9 through the trough or receptacle, preferably I provide an endless belt 10, the blocks being preferably delivered from the press as directly as possible upon the belt and conveyed thereby through the trough. In order to prevent the accumulation of block crumbs in the trough and to provide a simple and cheap but effective construction, the upper run only of the conveying belt 10 is received within the trough or receptacle. Preferably both the block receiving and block discharging ends of the belt extend longitudinally beyond the trough. As represented most clearly in Fig. 1, the block receiving end of the belt 10 is mounted upon a guiding drum, head pulley or other support 11 mounted in bearings in suitable brackets 12 exteriorly of the trough, and the block discharging end of the belt is mounted, as shown in Fig. 6, upon a driving drum or head pulley 13, also supported exteriorly of the trough in a manner to be hereinafter more particularly described. Intermediate the supporting drums 11 and 13, the upper run of the belt is supported within the trough at suitable intervals upon rolls 14, which as shown most clearly in Fig. 7 are loosely mounted upon roll shafts 15 journaled at 16 in the side walls of the trough. The lower run of the belt is supported by rolls 17, which, as shown most clearly in Fig. 7, are also loosely mounted upon roll shafts 18 journaled in the vertical sides 5 of the chairs 4.

While the blocks may be discharged directly from the trough into cars or the like or be distributed from the trough about the yard, I have herein represented in Figs. 3 to 6 inclusive, a support for the discharge end of the belt and the head pulley 13, and herein consisting of a framing made up of suitable uprights 19, cross and longitudinal

pieces 20, braces 21 and top channel irons 22 suitably connected and having journaled therein the end drum or head pulley 13 previously referred to, and rolls 14 and 17, similar to those journaled within the trough and the chairs respectively. Certain of these rolls are represented at 14' in Fig. 4 as enlarged in diameter and flanged at their ends, in order suitably to guide and support the belt 10.

While any suitable means may be employed to drive the belt, I have represented power as applied to the drum 13, and to this end have journaled in suitable hangers 23 shown in Figs. 1 and 7 as extending laterally from a side wall of the trough 2, the shaft 24, having mounted thereon a pulley 25, to which power is applied from any suitable source. The shaft 24 is herein represented as extending the entire length of the trough 2, and as having fast thereon at the discharge end of the trough a sprocket pinion 26 connected by a suitable sprocket chain, not shown, with a sprocket wheel 27 fast upon a shaft 28 extending longitudinally of and suitably journaled in the end support or framing and provided at its forward end with a sprocket wheel, not shown, and connected by a suitable sprocket chain with a sprocket wheel 29 fast upon a countershaft 30 having thereon a worm 31 meshing with a worm wheel 32 fast upon the shaft 33 carrying the drum or head pulley 13. By the described gearing or by any other suitable driving means, the belt 10 may be driven at any suitable speed.

I have obtained good results by driving the belt 10 at a speed somewhat greater than that at which the blocks are discharged from the press 1 by the ejecting head, so that as the blocks are received from the platform of the press upon the belt 10, as shown in Figs. 1 and 2, they are slightly separated from each other by the action of the belt 10, thus insuring the most effective cooling of the blocks.

If desired, and as shown in Fig. 2, I may provide a carrier plate 33 supporting the belt 10 and the blocks 9 as the latter enter the trough and at the discharge end of the belt I may provide a plate or guide 34, by which the blocks may be conveyed to a car or other point of storage or use.

As previously stated, the lower run of the belt is supported and returned below the trough 2. When, therefore, the block cooler remains idle for any substantial length of time, as for example, over Sundays or holidays, that portion of the belt which is outside of the trough becomes very dry and therefore elongated to such an extent as to prevent the belt being driven when power is thereafter applied in the usual manner. I have previously endeavored to meet this

contingency by providing means to adjust the bearings of the shaft whereon the drum or head pulley 13 is mounted, but owing to the great length and weight of the belt necessarily employed, and the loss of time incident to a manual adjustment of the parts, but mainly because after the belt has been tightened and the operation has been resumed, the belt is soon found to be too tight owing to the fact that the lower and previously dried run thereof has become wet and has contracted, it has been found impracticable to tighten the belt in this manner. I have therefore employed an automatic belt tightener to take up slack as formed, thus overcoming the objections to which I have referred. To this end, I have in Fig. 6, represented a lever 35 suitably mounted upon the end support or framing and having at one end a preferably flanged roll 36 contacting with the under face of the lower run of the belt as shown, the opposite end of the lever 35 being counterweighted as by means of an adjustable weight 37. In this manner, the slack of the belt is taken up as it occurs, thus avoiding the loss of time necessitated in taking up the slack manually in the manner heretofore attempted by me, and also permitting the self adjustment of the lever 35 and roll 36 when the entire belt becomes again wetted, and therefore contracts in length, as is inevitably the case when the operation of the parts is resumed. If desired, I may also provide a guide roll 38 mounted co-axially with the pivotal point of the lever 35.

As previously stated, the blocks are discharged from the press onto the belt 10 at a high temperature which may approximate 300° F. It is important not only that the blocks be subjected as soon as they are received in the trough to the action of a cooling liquid, which is at a sufficiently low temperature at the point where the blocks are received in the trough, but that throughout the greater and preferably the entire extent of their travel through the trough, the blocks be constantly subjected to the action of a liquid kept at all times at a sufficiently low temperature to act upon the blocks and most effectually to cool the same. By the present invention, I accomplish this result by introducing the cooling liquid into the trough at a plurality of points distributed longitudinally along the same and preferably at or near the bottom of the trough and at the same time I constantly withdraw the water as heated by the blocks, thus permitting fresh incoming water to take its place. As the water or other cooling liquid heated by contact with the blocks and after imparting its cooling action thereto, rises to the surface, if introduced in the manner disclosed in the present embodiment of the in-

vention, I constantly remove it therefrom in 65 preferably a thin film, layer, or sheet, and this I most effectively accomplish in this embodiment of the invention by providing a dam along one lateral wall of the trough and preferably extending the entire length 70 thereof.

In Fig. 3, I have represented a pipe 39 communicating with any suitable source of water or other cooling liquid supply, this pipe being supported by suitable brackets 75 adjacent and extending longitudinally of one lateral wall of the trough. At suitable points along the trough the pipe 39 is provided with suitable branch pipes 40 shown most clearly in Fig. 7, and each having a 80 valve 41 by which water may be admitted through each of the said branch pipes or cut off from any one of them. The pipe 39 is represented as extending the entire length of the trough and at one end of the trough, as, 85 for example, in this embodiment of the invention, at the discharge end thereof, is of maximum diameter, as represented at 41'. Certain succeeding lengths of the pipe are made of successively reduced diameters, 90 owing to the constant discharge of a portion of the body of water into the trough by the various branch pipes 40 distributed along the length thereof.

It will be apparent that if at any point 95 along the length of the trough I find the surface water sufficiently cool to act efficiently upon the blocks, I may cut down or cut off the incoming water supply at the branch pipe or pipes 40 nearest thereto, 100 thus preventing waste of water and making certain that only heated water is discharged. If at any point I find the surface water is becoming unduly heated I open or further open the valve or valves 41 nearest this 105 point to admit an additional supply of cold water at this point. The branch pipes 40 preferably discharge the water into the trough 2 closely adjacent the bottom thereof and beneath the upper run of the belt 10. 110

In Fig. 7, I have represented the lateral wall 43 of the trough, being the wall opposite that through which the cooling liquid is entered, as lower than the opposite wall 44 and as provided exteriorly and along 115 preferably the entire length thereof with angle irons 45, upon which is suitably supported a joint plate 46. Connected to the angle irons 45 in the manner shown are other angle irons 47, to which are secured by bolts 48 a dam 49 preferably ranging the entire length of the trough, and a gutter 50, 120 preferably inclined from end to end or to its point of ultimate discharge. The gutter 50 is here shown as extending the entire 125 length of the trough 2 and as having a sufficient drop to carry off the water discharged over the dam 49.

Preferably the upper edge of the dam 49 should be at such a level as to permit only a thin or surface film of water to be discharged thereover into the gutter 50, and preferably the heated water should be discharged over this dam at all points along the length of the same. As the trough may be of very considerable length, frequently ranging over 100 feet, it is a matter of considerable difficulty so to position the upper edge of the dam 49 that at all points the water may continuously discharge thereover, and in a preferably thin film or sheet. I may accomplish the desired result by rendering the dam 49 vertically adjustable in any suitable manner as by attaching it to the angle irons 47 with capacity for such adjustment. Preferably, however, I form the dam 49 of wood, and if in testing the same I find that the water is not discharged thereover at all points, I plane off the upper edge at those points where the water is not discharged. In this manner, I readily and at slight expense provide a lateral discharge extending the entire length of the trough.

From the foregoing description, it will be apparent that the heated blocks are received directly from the press by the belt 10 and are thereby conveyed without manual manipulation through the trough. During their travel therethrough they are constantly subjected to the action of a sufficiently cool liquid, a fresh supply of cold water or other suitable liquid being introduced at a number of points along the length of the trough, thus preventing the water from becoming overheated at any point. The cold water rises from the bottom of the trough into contact with the blocks supported upon the belt 10, and as the heat of the blocks is given up to the water, the now heated water rises to the surface and is discharged in a film or thin sheet in the described manner along preferably the entire length of the trough.

By reason of the automatic belt tightening means, the belt is kept taut at all times, so that even after extended interruptions in the use of the apparatus and the consequent drying of portions of the belt, the belt can be started up without loss of time and without the readjustment heretofore rendered necessary when the entire belt has become wetted after a period of idleness.

Having thus described one type or embodiment of my invention, I desire it to be understood that although specific terms are employed, they are used in a generic and descriptive sense and not for purposes of limitation, the scope of the invention being set forth in the following claims.

Claims.

1. An asphalt block cooler comprising in

combination an elongated trough or receptacle having one lateral edge lower than the other to constitute a lateral discharge, a side gutter into which said trough discharges, means to admit a cooling liquid at the bottom of the trough at a plurality of points spaced longitudinally along the same, and means to traverse blocks through said trough longitudinally thereof.

2. An asphalt block cooler comprising in combination an elongated trough or receptacle for the reception of the blocks to be cooled, and having one lateral edge lower than the other for the side discharge of the surface liquid and a strip secured along said lower edge and presenting a level upper edge for the discharge of the surface liquid thereover along its entire length and means to admit cooling liquid to said trough.

3. An asphalt block cooler comprising in combination an elongated trough or receptacle having one lateral edge lower than the other to constitute a lateral discharge, and a side gutter into which said trough discharges, the bottom of said gutter being inclined toward the outlet and means to admit cooling liquid to said trough.

4. An asphalt block cooler comprising in combination an elongated trough, a block conveying belt having one run thereof only contained in said trough, near its bottom; cooling fluid admission means effective near the bottom of said trough and liquid discharge means effective at the top of the contained liquid, whereby said belt is situated as closely as is practicable to the bottom of said trough where the most recently admitted and hence coolest liquid is situated.

5. An asphalt block cooler comprising in combination an elongated trough or receptacle, means to traverse blocks therethrough longitudinally thereof, pipes to admit cooling liquid to the bottom of the trough at a plurality of points spaced longitudinally along the same, a separate valve for each of said pipes, and a discharge dam arranged along one side of the trough, whereby the heated surface liquid may be discharged by separating it from the body of the liquid.

6. An asphalt block cooler comprising in combination an elongated trough or receptacle having one lateral edge lower than the other to constitute a lateral discharge, means to admit a cooling liquid adjacent the bottom of the trough at the side opposite the lateral discharge edge, and at a plurality of points spaced longitudinally along the trough and means to traverse blocks through the trough longitudinally thereof.

7. An asphalt block cooler comprising in combination an elongated trough or receptacle having a plurality of cooling liquid admission openings spaced longitudinally of the trough, and a single liquid supply pipe

arranged in substantial parallelism with
said trough and communicating by branch
pipes with each of said admission openings,
said pipe being of maximum diameter at the
5 first admission opening and successively re-
duced adjacent each subsequent admission
opening.

In testimony whereof, I have signed my
name to this specification, in the presence of
two subscribing witnesses.
